BILLIARD TABLE OR SIMILAR ARTICLE

Charles M. O'Leary, 525 S. Irving Blvd.,
Los Angeles, Calif. 90005

Filed Nov. 22, 1968, Ser. No. 14,600

Term of patent 14 years

Int. Cl. D21—01

U.S. Cl. D34—3

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 1 is a top plan view of a billiard table or similar article showing my new design;

FIG. 2 is a side elevational view looking from the bottom of FIG. 1;

FIG. 3 is a bottom plan view;

FIG. 4 is a side elevational view looking from the right-hand side of FIG. 1;

FIG. 5 is a top plan view showing a second embodiment of my new design wherein four pockets are provided;

FIG. 6 is a side elevational view looking from the bottom of FIG. 5;

FIG. 7 is a top plan view showing a third embodiment of my design wherein eight pockets are provided;

FIG. 8 is a side elevational view looking from the bottom of FIG. 7;

FIG. 9 is a top plan view showing a fourth embodiment of my design which is without pockets;

FIG. 10 is a side elevational view looking from the bottom of FIG. 9;

FIG. 11 is a top plan view showing a fifth embodiment of my design which is hexagonal; and

FIG. 12 is a side elevational view looking from the bottom of FIG. 11.

The sides opposite those shown in FIGS. 2, 4, 6, 8, 10, and 12, are substantially similar to those shown. The bottoms of the second, third, fourth and fifth embodiments shown in FIGS. 5 to 12 are substantially similar to the bottom of the first embodiment as shown in FIG. 3.

I claim:

The ornamental design for a billiard table or similar article, as shown and described.
